UNITED STATES PATENT OFFICE

EDUARD MAX VOIGT, OF KOENIGSBERG, GERMANY

COLLECTING CUP

Application filed June 20, 1928, Serial No. 287,027, and in Germany July 13, 1927.

My invention relates to a cup for collecting and saving the valuable waste produced during the working on articles made of precious metals. It is also suited to catch the article worked on should the latter slip from the hand, and thus save it from being damaged or lost. It can be held with the hand which usually holds the article to be worked on and follows every movement of the fingers holding said article, is always below the spot worked on, provides a rest for the hand manipulating the working tool and is therefore a useful and valuable instrument for dentists and all workers in precious metals who work on gold inlays, gold crowns, gold bridges, jewels and other articles made of such metals.

With these and other objects in view, the invention consists in certain novel features of construction as hereinafter shown and described and then specifically pointed out in the claims, and in the drawings illustrative of the preferred embodiment of the invention.

In the annexed drawing,

Figure 1 represents a perspective view of a collecting cup embodying my invention.

Figure 2 represents a view from one side.

Figure 3 represents a view from the opposite side.

Similar letters of reference indicate corresponding parts in the several figures.

According to the drawings, the collecting cup *a* consists of the bottom *r*, the front wall *b*, the back wall *c*, and the two side walls *n* and *m* which are lower than the front and back walls. In the side wall *n* are two openings *d* and *e*, and the bottom *r* has an inward bend or curve *g*.

When the cup is used the thumb is passed from the outside through the opening *d* and the ringfinger through the opening *e*. The forefinger and the middle finger rest on the rim of the side wall *n*. The small finger supports the cup *a* by being placed in the bend or curve *g* of the bottom *r*. If more convenient, the middle finger can be substituted for the ringfinger and passed through the opening *e*, and the ringfinger can support the cup by taking the place of the small finger in the curve *g* of the bottom *r*.

The fingers which are passed from the outside into the interior of the cup can hold the article to be worked on in the usual way without hindrance from the cup. The other hand holding the working tool reposes on the rim *i* of the low side wall *m* as shown in Figure 1 where the hand holds the handle *k* to operate the grinding stone *o* which by a shaft passing through the handle *k* and the flexible shaft *p* is connected with the motor of the dental drilling and grinding machine.

I wish it to be understood that I do not desire to be limited to the exact details of construction shown and described, for obvious modifications will occur to a person skilled in the art.

What I claim is:

1. A collecting cup for the purpose set forth having a bottom, a front wall, a back wall, a side wall, and another side wall provided with openings for the fingers which are to hold the cup and the article to be worked on.

2. A collecting cup for the purpose set forth having a bottom, a high front wall, a high back wall, a low side wall provided with openings for the fingers which are to hold the cup and the article to be worked on and also having a rim for the repose of the other fingers holding the article to be worked on, and a low side wall provided with a rim for the support of the hand holding the working tool.

3. A collecting cup for the purpose set forth having a front wall, a back wall, a side wall provided with openings for the fingers which are to hold the cup and the article to be worked on, a side wall having a rim for supporting the hand holding the working tool, and a bottom provided with an inward bend or curve adapted to place in it, for the purpose of supporting the cup, one of the fingers of the hand holding the cup and the article to be worked on.

In testimony whereof I affix my signature.

EDUARD MAX VOIGT.
